UNITED STATES PATENT OFFICE

RAYMOND H. DIETRICH, OF DETROIT, MICHIGAN

DESIGN FOR A HOOD FRONT ORNAMENT FOR MOTOR VEHICLES

Application filed March 12, 1931. Serial No. 39,055. Term of patent 7 years.

To all whom it may concern:

Be it known that I, RAYMOND H. DIETRICH, a citizen of the United States, residing at Detroit, in the county of Wayne and State of Michigan, and having my post-office address at 826 Fisher Building, Detroit, Michigan, have invented a new, original, and ornamental Design for Hood Front Ornament for Motor Vehicles, of which the following is a specification, reference being had to the accompanying drawings, forming part thereof.

In the drawings, Figure 1 is a front elevation of this ornament.

Figure 2 is a side elevation of parts seen in Figure 1.

This design consists of a base having cloud-

like figures thereon and a superposed fanciful figure simulating an aeroplane with a comparatively short wing and a central upstanding fin, the whole giving an impression of a birdlike or aeroplane figure sailing above the clouds.

I claim:

The ornamental design for a hood front ornament for motor vehicles substantially as shown and described.

In testimony whereof, I have hereunto signed my name, at Syracuse, in the county of Onondaga, and State of New York, this 9th day of March, 1931.

RAYMOND H. DIETRICH.
